UNITED STATES PATENT OFFICE.

LOUIS W. NIMSCHKE, OF NEW YORK, N. Y.

MANUFACTURE OF BRUSHES.

SPECIFICATION forming part of Letters Patent No. 400,475, dated April 2, 1889.

Application filed September 20, 1887. Serial No. 250,171. (No model.)

To all whom it may concern:

Be it known that I, LOUIS W. NIMSCHKE, of the city, county, and State of New York, have invented certain new and useful Improvements in the Manufacture of Brushes, of which the following is a specification.

This invention relates to certain improvements in the manufacture of hair and other brushes; and the invention consists of a brush of novel construction, as will appear more fully hereinafter, and finally be pointed out in the claim.

In the accompanying drawings, Figures 1 and 3 represent a vertical longitudinal section of the mold employed for filling the base-plate of the brush with bristles. Fig. 2 is a top view of the bristle-holding base-plate. Fig. 3 is a vertical longitudinal section of a modified form of the filling-mold, and Fig. 4 is a vertical longitudinal section of the brush-base attached to a brush-back.

Similar letters of reference indicate corresponding parts.

In the drawings, A represents a bristle-holding base-plate, which forms the novel feature of my improved brush, and which is made of brass, tin, or other suitable soft metal, and of the shape and size of the brush to be manufactured. The base-plate A is provided with a number of bent-up points or prongs, a, which are made integral with the body of the base-plate and set into correspondingly-arranged socket-holes of the base-block B' of the mold B. The base-block B' is provided with vertical guide-pins b b, that are screwed into said block, said pins serving to guide the filling top block, B², of the mold B. The base-plate A is provided with a number of perforations, d, which are provided with conically-tapering rims d', that project either from the under side or from the top of the base-plate A, as shown, respectively, in Figs. 1 and 3. The top block, B², of the mold B is provided with as many holes as there are perforations in the base-plate A, said holes serving for the purpose of filling the rimmed perforations d of the base-plate A with bristles. The base-block B' is provided vertically below and in line with the filling-holes of the top block, and the perforations of the base-plate with conically-tapering depressions d², of such a na-

ture that the inclination of their tapering sides is somewhat steeper than the inclination of the tapering rims, so that on lowering the top block, B², by suitable pressure exerted thereon, the tapering rims of the base-plate A are contracted at their edges by the depressions of the base-block, and thereby the tufts of bristles that have been filled through the holes of the top block retained firmly by the contracted rims of the base-plate A. This arrangement is shown in Fig. 1, in which case base-plates are produced in which the tapering rims project at the under side of the plate and bind rigidly on the lower ends of the tufts. In place of arranging the tapering depressions on the base-block, they may also be arranged at the lower ends of the filling-holes of the top block, B², as shown in Fig. 3, which arrangement is used when the tapering rims project from the upper part of the base-plate, as shown in Fig. 3. In this case the inclined sides of the tapering depressions are arranged at a smaller angle of inclination to the axis of the filling-holes than the outer tapering surfaces of the rims to the axis of the perforations of the base-plate A, so that on depressing the top block, B², by suitable pressure, the edges of the tapering rims are contracted and closed tightly on the tufts of the bristles supplied through the openings of the top block, B², to the rimmed perforations of the base-plate A. The base-plate A, with the tufts, is then removed from the filling-mold and applied by the spurs a a and a suitable layer of cement to a back, C, of wood, rubber, or other suitable material, which back extends around the base-plate, the rim of the brush-back being flush with the face of the base-plate when the construction shown in Fig. 1 is used, while in the construction of the base-plate shown in Fig. 3 the tapering and contracted bristle-holding rims project above the face of the back.

This method of constructing brushes is adapted to all kinds of brushes—such as hair-brushes, clothes-brushes, blacking-brushes, &c.—and produces a cheap, strong, and durable brush, as the bristle-holding base-plate can be cheaply made of suitable cast metal, or pressed in dies when metal of sufficient ductility and softness is employed.

Having thus described my invention, I claim as new and desire to secure by Letters Patent—

A brush composed of a back, a metallic base-plate secured to said back, said base-plate having openings with tapering rims, and tufts of bristles inserted into said openings and retained by compressing the upper portion of the rims upon the bristle tufts, substantially as set forth.

In testimony that I claim the foregoing as my invention I have signed my name in presence of two subscribing witnesses.

LOUIS W. NIMSCHKE.
